SIGN

Application filed May 21, 1930. Serial No. 454,374.

Our present invention has reference to an illuminated sign of changing colors and our primary object is to provide an illuminated sign that will enable the sign letters and face 5 to be illuminated with different color effects as the lantern in the sign housing revolves.

A further object is to provide a sign that includes a housing having a face plate provided with transparent letters, a cylindrical 10 lantern journaled for rotation in the housing and comprising a member which is translucent and variably colored, the said lantern having arranged therein any desired number 15 of stationary lamp bulbs and a reflector therefor, together with air wheels or propellers for operating a train of gears for imparting rotation to the lantern so that the rays of light from the lamp bulbs will permeate through 20 the lantern and through the sign on the face of the housing and thereby produce an artistic and attractive effect.

To the attainment of the foregoing the invention consists in the improvement hereinafter described and definitely claimed.

25 In the drawings:

Figure 1 is a perspective view of a sign in accordance with our invention.

Figure 2 is a sectional view approximately on the line 2—2 of Figure 1.

30 Figure 3 is a face view with the sign plate removed and parts of the improvement in section.

The casing or housing of our improvement is preferably in the nature of a semi-cylindrical member. The housing 1 has its flat 35 face closed by a plate 2 which is preferably of translucent material and which has arranged thereon sign letters 3 which are transparent. Journaled through the ends of the housing 40 there is a tubular shaft 4, held stationary in any desired manner, and through one end of this shaft there are received the encased wires 5 that are connected to any desired number of lamp bulbs 6 which have their bases 45 screwed in suitable openings in the stationary shaft 4. The lamp bulbs also sustain on the shaft 4 a reflector 7 which is of concavo convex cross section. The bulbs 6 and reflector 7 are received in a transparent or 50 translucent cylindrical lantern 8. The lan-

tern has both of its ends journaled on the shaft but one of the ends, indicated by the numeral 9, is in the nature of a cap member and is provided with a series of equidistantly spaced apertures or openings 10. These openings are engaged by teeth on a pintle 11. The pintle is journaled on a suitable stub shaft 12 secured to one end of the housing 1, and on the said stub shaft there is fixed one of a train of gears 13, one of such gears being engaged by a pinion 14 on a shaft 15 that extends longitudinally through the housing 1. This shaft has fixed on the ends thereof which project through the housing wind 55 wheels 17.

The device is positioned so that the wheels 17 will be contacted by the wind and thereby revolve the shaft 15 and the train of gears to impart a rotary motion to the lantern 8. The lantern 8 is variably colored, as indicated by 70 the characters 18, and the rays of light from the bulbs 6 will penetrate through the colored lantern and through the sign 3 on the outer face of the housing 1. The revolving lantern will cause the colors thereon to blend 75 as they penetrate through the transparent sign 3 and thus afford not only an artistic and pleasing effect but afford a means which cannot fail to attract attention to the sign.

It is believed that the foregoing description when read in connection with the accompanying drawings will fully set forth the operation and advantages of our improved sign and that further detailed description will not be required. Obviously we do not 80 wish to be restricted to the precise details herein set forth and, therefore, hold ourselves entitled to make such changes therefrom as fairly fall within the scope of what we claim.

Having described the invention, we claim:

1. A sign including a housing having a translucent face provided with transparent letters, a fixed shaft extending longitudinally through the housing, sources of light on the shaft, a reflector fixed on the shaft for such sources of light, a cylindrical lantern of transparent material mounted for rotation on the shaft, and said lantern being variably colored, said lantern having a cap end which is peripherally apertured, a pintle engaging 95

the apertures, speed decreasing gears in the housing, one of which being fixed to the pintle, a shaft journaled through the ends of the housing fixed on one of the gears and wind wheels on the outer ends of the shaft.

5. 2. A sign including a housing having transparent sign letters on the outer face thereof, a tubular shaft extending longitudinally through and fixed to the ends of the housing, lamp bulbs having their bases screwed in the shaft, a cross sectionally concavo convex reflector fixed on the shaft for the bulbs, a conductor leading through one end of the shaft and connected with the bulbs, a cylindrical lantern journaled on the fixed shaft, and comprising a member of translucent material having a variable colored face, a train of gears for revolving the lantern and wind wheels for operating such gears.

20. In testimony whereof we affix our signatures.

JAMES FREDERICK WINER.
NATHAN NEWSOM MAYO.
